UNITED STATES PATENT OFFICE.

JOHN M. FITZ GERALD, OF OAK PARK, ILLINOIS.

CARRIER-SUPPORT FOR SIGNAL AND SWITCH RODS.

1,288,399.

Specification of Letters Patent. Patented Dec. 17, 1918.

Application filed April 13, 1918. Serial No. 228,365.

To all whom it may concern:

Be it known that I, JOHN M. FITZ GERALD, a citizen of the United States, and resident of the village of Oak Park, in the county of Cook and State of Illinois, have invented certain new and useful Improvements in Carrier-Supports for Signal and Switch Rods, of which the following is a specification.

10 The present invention and improvements relate to means for supporting the carriers used along railway tracks for holding the push-and-pull rods leading from signals and switches to the tower or other station from which the switches or signals are controlled. These rods are ordinarily in the form of metallic pipes, this form combining lightness with the desired strength.

15 In one aspect of the present disclosure it constitutes an improvement upon the device or devices set forth in U. S. Letters Patent No. 1,247,810, of November 20, 1917 to J. C. Mock, entitled "Pipe carrier support." In another aspect it has more generic properties.

20 The primary objects of the improvement are to simplify the construction set forth in said Letters Patent and to render more rapid simple and easy the desired proper lateral adjustment of the carrier at the time of installation, or from time to time as may be required; and, in its more generic characteristics, the object of the invention is to provide a carrier holding device in which, in 25 one feature, a considerable number of rod carriers may be secured together, the desired distance apart, in a unitary structure, with means for adjusting this unitary structure laterally as desired, thereby simultaneously 30 adjusting all of the rods; and in another view to provide a device of this kind in which two bolts, for instance, one at each side of the supporting pier or foundation, at once maintain the above mentioned unitary 35 structure rigidly upon the pier as well as in the proper relation of adjustment thereon. An auxiliary object is to provide a structure of such proportions as make it applicable to piers or foundations already installed and 40 without any other modification of the system than to apply the new form of pedestal

and carrier-supporting rails. Other objects and advantages will appear hereinafter.

In the accompanying drawings, which 55 form a part of this specification, I have illustrated the new construction in what I now consider to be its most advantageous forms, Figure 1 being a perspective view of the preferred form of the device complete, as in use, with one pair of rod carriers operatively 60 thereon;

Fig. 2 is an enlarged medial section of the corner portion of the device of Fig. 1 which is directed toward the observer;

Fig. 3 is a fragmentary side view of the 65 end portion of a slightly modified construction; and

Fig. 4 is a fragmentary end view of the structure of Fig. 3.

Referring to Fig. 1 the pier or foundation 70 10 may be of any suitable material, and is usually of concrete. It is ordinarily flat on top. The general practice has been to secure a piece of wood upon this flat top surface, as by means of bolts 11 having an end 75 portion 12 turned at right angles and adapted to be positioned in a hole in the concrete pier as shown, the rod carriers then being secured to the wood block by means of lag screws. My present invention and improvements 80 contemplate the use of the pier 10 and bolt 11, as in current practice, but with the removal of the wood block mentioned.

Resting upon the pier 10 is a pair of brackets or pedestals 14, each having a pair 85 of feet 15 constituting a bearing adapted to rest upon the pier 10. Each pedestal has also a pair of openings 16, shown as recesses which are undercut at the sides, or, in other words, of truncated-cone shape in transverse view. The feet or bearings 15 and the recesses 16 are shown as being at substantially equal distances from a medial vertical line through the pedestals respectively, the recesses being directly over the feet 90 respectively when in normal position for use. The bearing 15 may, however, be continuous and may be otherwise shaped, the desideratum being that it shall provide for a rocking of the pedestal thereon upon the foundation 100 on an axis which is cross-wise of the general direction of the rails when held in the open-

ings or recesses 16. In my practice, and as illustrated, the rocking of the pedestals is on an axis substantially at right angles to the vertical planes in which the rails, when 5 properly positioned, lie. It is obvious, also, that the foundation may be otherwise formed than as a flat top of a concrete pier.

The two pedestals 14 may be in all respects alike, and are so shown, it being feasible to employ the identical construction at 10 each side of the pier 10. The two pedestals need not, however, be mounted on the same pier or other foundation.

Two rails 20 interfit slidably with the 15 openings, grooves or recesses 16 respectively as shown, and are retained therein by the overhanging walls. Where the openings 16 are of the truncated-cone shape the rails are preferably of the same shape in cross view, 20 as illustrated in Figs. 1 and 2. Upon the rails 20 the pipe carriers 30 are secured, by means of bolts 31, there being holes 32 in the rails the proper distance apart to receive these bolts.

25 The pipe carriers 30 are of well known and standard construction and comprise a grooved roller 33 mounted on a stud shaft 34 adapted to roll in a normally horizontally disposed bearing slot 35, and adapted to 30 carry the rod 36, usually an iron pipe, as stated hereinabove. A second roller 37 on a stud shaft 38 maintains the pipe or rod 36 in its operative position. Each carrier 30 has a pair of projecting feet 39 having bolt 35 holes for the bolts 31.

In practice the rail openings or recesses 16 are so spaced apart that the middle of each thereof substantially coincides with the bolt holes for the bolts 31 in the feet of the carriers 30.

In the modification of Figs. 3 and 4 tubular rails 45, being suitably iron pipe about one and one-quarter inches in diameter, are shown, and the openings or recesses 46 with 45 which they slidingly interfit, are also on circular lines in transverse view. The feet 39 of the carriers 30 are held on the rails by hook-bolts 47 encompassing the lower surface of the rails. The carriers 30 are thus held rigidly and adjustably on the rails 45. In this construction the pedestal 48 is notably narrower and more compact than is the pedestal 14. The pedestal 48 has feet 15 constituting a bearing adapted 55 to rest upon the foundation or pier 10.

The principles involved and the construction by which the rails 20 and 45 and the entire structure are held in the desired operative position are common to both forms 60 illustrated and will be described in connection with common reference characters.

It will be noted that the general direction of the openings or recesses 16 and 46 are on lines upwardly diverging from the horizontal 65 in a direction away from the bolt 11,

when the feet 15 are resting flatly upon the foundation. This will be clear from the cross section of Fig. 2 and from the dotted line of Fig. 3. In order, therefore, that the rails 20 and 45 may slide in these openings 70 or recesses it is essential that the pedestals be tipped inward or toward each other somewhat, so that the recesses may be on lines substantially parallel with the rails. This tipped over position is shown by dotted 75 lines in Fig. 2. Each of the pedestals is provided with a lug or projection 50, strengthened by webs 51, and located midway between the rail openings 16 and 46 respectively. Each lug 50 is materially spaced 80 upward from the horizontal plane of the feet 15 and is apertured to receive the end of a bolt 11, and these apertures are materially spaced outward from the vertical planes of the bearing surfaces on the feet 15. These 85 projections therefore constitute leverage means which are made effective through the tightening down of the nuts 52 on the bolts 11. When the nuts 52 are so tightened down, the pedestals 14 and 48 respectively are 90 rocked on their feet or bearing surfaces and the rails, 20 in one case and 45 in the other, are clamped, pinched or bound by the walls about the recesses 16 and 46 respectively. This will be clear from Fig. 2, showing in 95 full lines the pedestal 14 drawn down solidly upon the foundation 10, the feet 15 resting flatly thereon, and the direction of the groove or opening 16 being materially out of coincidence with that of the rail 20. Figs. 100 3 and 4, which also show the pedestals tightened down, illustrate also how the rail is clamped. In both forms the rail is contacted by the bottom of the recess 16 or 46 at its innermost part, or that part farthest 105 from the bolt 11, and by the overhanging walls at the top of the recesses nearest to the bolt 11. In other words, the leverage action of the bolt 11 in the lug 50 causes a canting action between the rails and the walls forming 110 the grooves of the pedestal.

It will now be clear that the single bolt 11 performs the double function of holding the pedestal upon the foundation and holding the rails against any movement relative 115 to the pedestal. It is also clear that by merely loosening the nuts 52 the entire system of rod carriers there supported may be moved laterally, as a unit. This is a notable advantage in the saving of time and effort 120 and in the certainty of maintaining the carriers at their proper distances apart.

An advantage of the rail construction shown in Figs. 1 and 2 is in the fact that these rails may be lengthened by bolting a 125 tie piece 60 of the same material on the undersides of two rails, as by bolts 61, Fig. 1.

When, therefore, it is desired to widen the system of carriers it is not necessary to dismantle the structure already installed, 130

but additional sections of rail material may simply be added as shown. It will be understood that if such rails be extended to a considerable distance beyond one foundation 5 they will be suitably supported at their extended ends, as by an additional pedestal or pedestals 14.

The pedestals may be made of gray iron castings. The rails 20 are of rolled wrought 10 iron, and the rails 45 of common iron pipe.

Various changes may be made in the arrangement and construction of parts within the spirit of the invention and improvements herein set forth, and I contemplate 15 all such as fall within the scope of the appended claims.

I claim:

1. In a rod-carrying device of the character described, the combination of a foundation, 20 a pedestal having a bearing and mounted to rock thereon upon said foundation on an axis extending in the general direction of the rod to be carried, said pedestal having rail openings substantially at right angles to the direction of the rod to be carried, a rail retainingly held in and slidingly interfitting with each of said openings, a rod carrier mounted on said rails, said pedestal having leverage means materially spaced 30 from the vertical plane of said bearing for tightening the pedestal upon said foundation and for simultaneously rocking the pedestal to bind the same upon said rails.

2. In a rod-carrying device of the character described, the combination of a foundation, 35 a pair of rail-supporting pedestals spaced apart and facing each other on said foundation, one of said pedestals having a bearing and mounted to rock thereon upon said foundation on an axis extending in the general direction of the rod to be carried, said pedestal having rail openings substantially at right angles to the direction of the rod to be carried, a rail retainingly held in and slidingly interfitting with each of said openings, a rod carrier mounted on said rails, said pedestal having leverage means materially spaced from the vertical plane of 45 said bearing for tightening the pedestal upon said foundation and for simultaneously rocking the pedestal to bind the same upon said rails.

3. In a rod-carrying device of the character described, the combination of a foundation, 55 a pedestal having a bearing and mounted to rock thereon upon said foundation on an axis extending in the general direction of the rod to be carried, said pedestal having rail openings substantially at right angles to the direction of the rod to be carried, a rail retainingly held in and slidingly interfitting with each of said openings, a rod-carrier mounted on said rails, said pedestal having a leverage part extending materially beyond the vertical plane of 60 said

bearing and having a normally vertical bolt hole materially beyond said last mentioned plane, and a bolt secured to said base and extending through said hole for tightening the pedestal upon said foundation and for 70 simultaneously rocking the pedestal to bind the same upon said rails.

4. In a device of the character described, the combination of a foundation, a pedestal having a bearing and mounted to rock 75 thereon upon said foundation on an axis extending in the general direction of the rod to be carried, said pedestal having a pair of spaced apart recesses of truncated-cone shape in transverse sectional view, a rail 80 of similar truncated-cone shape in transverse sectional view retainingly held and slidingly interfitting with said recesses respectively, means on said rails for holding a rod carrier, said pedestal having a part 85 extending materially beyond the vertical plane of said bearing, and bolt means associated with said extending part for tightening the pedestal upon said foundation and for simultaneously rocking the pedestal to 90 bind the same upon said rails.

5. In a device of the character described, the combination of a pedestal having openings to receive rod carrier supporting rails, and having a bearing adapted to rest and 95 rock upon a foundation on an axis substantially cross-wise of the normally vertical planes of said rails, rod carrier supporting rails slidably held in said openings, and tightening means for holding the pedestal 100 securely upon the foundation and for simultaneously rocking the pedestal to bind said rails in said openings respectively.

6. A rod-carrier pedestal for a device of the character described, comprising a structure having a pair of rail openings on a substantially horizontal plane when the pedestal is tilted in one direction, the openings being spaced apart and adapted to receive slidingly a pair of rails in substantially parallel and normally substantially horizontal arrangement, the pedestal structure having also a bearing normally below said openings and on which the pedestal may rock on an axis normally cross-wise of the 115 normal direction of such rails when in said openings, the structure also having a portion projecting materially beyond the vertical plane of said bearing when the device is in normal position for use, and means on said 120 projecting portion for engagement with a tightening element to tilt the pedestal in the reverse direction and to bind said rails in said rail openings.

7. A rod-carrier pedestal for a device of 125 the character described comprising a structure having a pair of rail-receiving openings spaced apart and a bearing normally beneath said openings and having an extension normally above said bearing and ma- 130

terially outside a vertical plane through said bearing, with means in said extension for engaging a tightening element held by an adjacent structure, for the purpose specified.

5. 8. In a device of the character described, the combination of a pedestal having a bearing

and retainedly mounted on the pedestal and extending in a direction crosswise of the axis of said bearing, and means for rocking 10 the pedestal on its axis to bind the same upon said rail.

JOHN M. FITZ GERALD.
